UNITED STATES PATENT OFFICE.

JOSEPH J. WALSER, OF ANN ARBOR, MICHIGAN, AND HARLAND FANKBONER, OF CHICAGO, ILLINOIS, ASSIGNEES TO GOSS PRINTING PRESS COMPANY, A CORPORATION OF ILLINOIS.

INKING MECHANISM.

Application filed March 12, 1920. Serial No. 365,355.

To all whom it may concern:

Be it known that we, JOSEPH J. WALSER and HARLAND FANKBONER, citizens of the United States, residing, respectively, at Ann Arbor, Mich., and in Chicago, in the county of Cook and State of Illinois, have invented certain new and useful Improvements in Inking Mechanism, of which the following is a specification.

10 The invention relates to printing press and more particularly to the inking mechanism and cooperating parts, the invention being directed and especially adapted in its chief aspects or features to inking mechanism fitted and adapted for fast rotary presses, such as are used for newspaper work and some magazine work.

Objects and advantages of the invention will be set forth in part hereinafter, and in 20 part will be obvious herefrom, or may be learned by practice with the invention; the same being realized and attained through the instrumentalities and combination pointed out in the appended claims.

25 The invention consists in the novel parts, arrangements, constructions, combinations and improvements herein shown and described.

The accompanying drawings, referred to 30 herein and constituting a part hereof, illustrate one embodiment of the invention, and together with the description serve to explain the principles of the invention.

Of the drawings:—

35 Fig. 1 is a fragmentary side elevation, partly diagrammatic, of the inking mechanism and a rotary printing couple of a printing press embodying the invention;

40 Fig. 2 is a fragmentary end elevation, with parts in section, looking at Fig. 1 from the right;

Fig. 3 is a detail with the parts separated of the adjustable cam for controlling the ductor roller;

45 Fig. 4 is an enlarged fragmentary detail taken in section substantially on the line 4—4 of Fig. 1;

Fig. 5 is a fragmentary elevation, partly diagrammatic showing the operation of the 50 fountain roller, ink drum and the ductor roller governing means; and

Figs. 6 and 7 are diagrammatic views illustrating the peripheral travel of the

ductor roller upon the periphery of the ink drum. 55

Referring now in detail to the embodiment illustrated by way of example in the accompanying drawings, a rotary printing couple is represented having a form cylinder 1 with its shaft 2 running in bearings 3, and a cooperating impression cylinder 4 having its shaft 5 running in bearings 6. The web α runs through between the cylinders in the usual manner and is printed upon by the plates upon the form cylinder 1. 65

In accordance with certain features of the invention, a ductor roller or like ink conveying device, or preferably a plurality thereof, are provided which travel along the periphery of the fountain roller, or of the 70 ink drum, or of both, the quantity and duration of the conveyance or transfer of ink from one of said members to another being controlled by the extent of such travel of the ductor roller along the periphery of one 75 or the other of said members, rather than by dwell or pause of the ductor roller in engagement with the ink drum or fountain roller. There is provided by the present invention an adaptation of a mechanism such as just described to an inking system having a plurality of fountain rollers (whether operating in a single ink fountain or in a plurality of fountains) and having a plurality of ink drums receiving ink from the 80 ductor rollers and conveying it to the same form or plate cylinder, thereby constituting a multi-supply inking mechanism. 85

In conjunction and cooperation with the foregoing, the invention provides, but is 90 not limited to, a reciprocating ductor roller, and preferably to a plurality of such ductor rollers diametrically disposed in one or more pairs. The manner of ink conveyance or transfer hereinbefore described renders 95 possible the employment of a continuously rotating fountain roller, and also the employment and cooperation as a joint inking means for a single form or plate cylinder of a plurality of such fountain rollers, although it will be understood that in its broader aspects, the invention is not so limited. 100

In conjunction with the feature of the reciprocating ductor roller or rollers, as distinguished from an endlessly traveling duc- 105

tor roller, the reciprocating ductor rollers are caused to travel in a path preferably circular and describing an arc somewhat longer than that defined or limited by or between 5 the common radius of the ductor roller support and ink drum and the common radius of the center of the ductor roller support and the fountain roller. This gives a possible longer path or extent of travel of the 10 ductor roller along the periphery of the ink drum or the fountain roller, or both, and therefore gives a wider range and control of the ink supply.

In accordance with certain features of the 15 invention, the ductor roller is resiliently impelled toward the ink drum and the fountain roller, thereby adapting and capacitating the ductor roller to effect and describe its travel along or over the periphery of 20 either or both of said other members, and in conjunction therewith settable or adjustable means are provided for moving or restraining the ductor roller, or rollers, against the action of their resiliently impelled means, to 25 limit or vary and to govern the extent of the travel of the ductor roller along the periphery of the ink drum or fountain roller. Such means further are provided in connection with each ink drum or fountain roller, independently of the adjustments or controls 30 for the others, in case a plurality of ink drums or fountain rollers, or both, are employed as already described. This provides a means for controlling the quantity and 35 condition of the ink conveyance and supply from each fountain roller independently, and the conveyance and supply to each ink drum independently and at the same time controlling the same collectively as supplied to the 40 plates upon the form cylinder 1.

More in detail as to certain features of the foregoing, a ductor roller reciprocates about a center in an arc extending somewhat beyond a fountain roller and beyond an ink drum with both of which the ductor roller cooperates, the ductor roller being resiliently impelled outwardly radially to have the desired travel along the periphery of the ink drum, and of the fountain roller, or both.

50 Preferably such ductor rollers operate in one or more diametrically disposed pairs, swinging about a common center by means of arms fixed to a common shaft, each ductor roller receiving ink from its own fountain roller, and each conveying ink to its own ink drum, the ink drums contributing together to ink a common form cylinder or rather the plates thereon. Each ductor roller is provided with its own settable governing devices, such as an adjustable cam or cams for pressing back in a radial direction the corresponding ductor roller, against its springs, more or less to limit and control the extent of its travel along the periphery of 55 the other member or members. The more

the ductor roller is held back against its springs, the less will be the extent of its peripheral travel on the ink drum and the fountain roller, and the less quantity of ink is transferred forward to the printing plates 70 on the form cylinder.

In the embodied form, these various features of the invention, while largely capable of separate and independent use, are associated together in a single mechanism and in cooperation one with another, and together with other features of the invention not heretofore mentioned, but which will be later described and pointed out.

80 Referring to the details of the illustrated embodiment, a plurality of ink fountains are shown, one ink fountain 10 having a fountain roller 11 therein, and another ink fountain 12 having a fountain roller 13 therein. Each fountain roller is rotated in the proper direction and at desired speed in any suitable manner, as by a usual type of gearing from the common machine drive (not shown.)

90 As embodied herein, and in accordance with certain features of the invention, as already pointed out, a plurality of ductor rollers are provided, shown herein as a pair of such rollers, 14, and 15, mounted respectively upon corresponding pairs of arms 16 and 17, which are fixed to a shaft or a corresponding pair of stub shafts, 18, journaled in the machine frame. Suitable means for 95 rocking or reciprocating the shaft 18 are provided, and as embodied, there is fixed to the shaft an arm 19, driven by suitable connections from a shaft 20. As embodied the arm 19 is double, the two parts being spaced apart and having a transverse wrist pin 21 100 mounted in the end thereof.

105 Pivottally mounted on the wrist pin 21 is a connecting rod 22, which rod at its other end is pivotally connected to another connecting rod 23. The rod 23 at its opposite end 24 is pivotally connected to the strap 25 of an eccentric 26, the eccentric being mounted upon the shaft 20. There is thereby imparted a reciprocatory or oscillatory movement in the 110 pair of arms 16, 17 and their respective ductor rollers 14 and 15 are swung to and fro along an arc which is somewhat longer than the distance between the respective common radii of the shaft 18 and the corresponding fountain roller and said shaft and the corresponding ink drum, to permit or render possible the full travel of the ductor roller along the respective peripheries of the ink drum and fountain roller, as desired.

115 In the embodied form of resilient mounting for the ductor rollers, the pairs of arms 16 and 17 have each arm near its external end, that is the end away from the shaft 18, provided with a closed bearing aperture 30. 120 In each of the bearing apertures 30 is a jour-

nal box 31 longitudinally or radially slidable in the aperture. In each journal box 31 is journaled a shaft 32 of one of the ductor rollers, the roller with its shaft 32 being 5 free to rotate in the journal boxes 31.

The embodied form of the resilient impelling means, operating preferably outwardly radially, as already indicated, comprises a coil spring 33 located in each ductor 10 roller carrying arm, in compression between the corresponding journal box 31 and the inner end of the corresponding aperture 30.

In the embodied form for moving or predeterminedly positioning the ductor rollers 15 with respect to the ink drums, or the fountain roller, or both (already referred to) the shafts 32 preferably project outwardly beyond their respective arms 16 and 17. Fixed to these projecting ends of the respective 20 shafts 32, are cam rollers 35, which in the present embodiment cooperate with the adjustable cam, which works against the spring 33, to radially vary and determine the position of the ductor rollers to govern the extent of their travel upon the respective peripheries of the ink drum or fountain roller, or both, to control the supply of ink to the printing plates on the press as already explained.

30 The embodied form of the cam control just referred to comprises an arcuate cam 36 located between the fountain roller 11 and its ink drum 37 or between the fountain roller 13 and its ink drum 38. The cam 36 is preferably multi-part, the parts being independently circumferentially adjustable or positionable with respect to each other, so as to regulate the place of incidence of the ductor roller both upon the fountain roller 40 and upon the ink drum.

A detail of the embodied form of the cam is shown in Fig. 3. The two circumferentially adjustable parts 39 and 40 are provided with adjusting slots, one slot 41 being 45 in the part 39, another slot 42 being the part 40, and two parts having common registering slots 43 where the parts 39 and 40 overlap. The various slots are provided with suitable clamping bolts 44, 45 and 46, threaded into the machine frame. The arms 16 and 17 and their respective ductor roller carrying slots 30 are so proportioned that when the respective springs 33 are permitted 50 to press the journal or bearing boxes 31 to the outer ends of the slots 30, the path of the outer part of the ductor roller would describe the arc or circle indicated by the line 47 in Fig. 5, and the extreme outer part of the roller 35 would describe the path indicated by the line 48 in Fig. 5. Thus the ductor roller will travel over the periphery of the other drum or roller, the springs 33 compressing and then expanding to permit 55 this motion. The cam rollers 35 are so proportioned that as they roll along the cams

they will be brought to the speed of the ink drum or of the ductor roller, respectively.

Due to this position of the path of the ductor rollers and to their resilient impulsion radially outwardly by the springs 33, 70 they are capacitated to travel or roll along the periphery of the ink drum 38, and the fountain roller 13, and of the ink drum 47 and the fountain roller 11, as the case may be. The circumferential and relatively independent adjustment of the parts 39 and 40 of the cam 36 govern or control the extent of such peripheral travel, as desired, with either the ink drum or fountain roller, 75 independently of the other. The provision of such means at each side obviously makes the adjustment or control of each side or part of the mechanism independent of the other.

By the circumferential adjustment of the part 40 of cam 36, the point of rise or departure of the ductor roller from the fountain roller can be exactly governed, thereby giving a nice and accurate control of the quantity of ink taken by the ductor roller 80 from the fountain roller. By the circumferential adjustment of the part 39 of cam 36 to or from the ink drum, the point in the travel of the ductor roller is determined at which it will come into contact with the 85 periphery of the ink drum, and thereby an equally nice and accurate control is obtained of the delivery of the ink from the ductor roller to the ink drum.

The remaining parts of the inking mechanism, shown herein more or less conventionally, comprise as so shown transferring rollers 50 and 51, form roller 52, ink drum 53, form roller 54 and a distributing roller 55 cooperating with form roller 52.

The ink drums 37, 38 and 53 and the roller 55, in the preferred form, are all vibrated, and the ink drums 37, 38 and 53 are likewise positively driven, in the usual manner while the roller 55 is frictionally driven from form roller 52. In the embodied form of vibrating means, there is fixed on the shaft 20 an eccentric 56, the strap 57 thereof being connected to a rod 58. The rod 58 is pivotally connected to an arm 59, which arm is fixed to a shaft 60 journaled in a bracket 61 mounted upon the machine frame.

Fixed to the shaft 60 is an arm 62, provided with a roller 63, which roller runs in an annularly grooved collar 64 formed upon the shaft 65 of ink drum 38. The ink drum is positively rotated from the other end of its shaft in a well-known manner. An arm 67 extends upwardly from the shaft 60 and is provided with a roller 68, said roller working in an annularly grooved collar 69 carried on the shaft 70 of the frictionally driven roller 55.

Fixed to shaft 60 is a geared sector 74,

with which meshes a geared sector 75, fixed to a shaft 76, which shaft is journaled in a bracket 77 carried on the machine frame. From shaft 76 an arm 78 extends downwardly and is provided with a roller 79, said roller working in an annularly grooved collar 80 on the shaft 81 of the ink drum 37. The ink drum 37 is likewise positively driven from the other end of its shaft in a well-known manner. From the shaft 76 an arm 84 extends upwardly and carries a roller 85, said roller working in an annularly grooved collar 86 on the shaft 87 of the ink drum 53, which ink drum, like the others, is driven from the other end of its shaft, in any known or approved manner.

The general operation of the mechanism will be clear from what has already been said. It will be noted in Fig. 5 that the circular path to, or toward which the ductor roller is resiliently impelled is indicated as 47, this being the path of the outer point on the periphery of the ductor roller. The inter-sections of arc 47 with the periphery 25 of ink drum 38 will measure the maximum travel of the ductor roller along the periphery of the ink drum. This travel involves a concurrent backward radial movement of the ductor roller against its resilient mounting, in this case the spring 33.

The actual path of the ductor roller from the point of incidence, however, is not the arc 47, but the arc of the periphery of the ink drum 38 which is included in the arc 35 47, except that this is modified by the position of the cam 36.

In Figs. 6 and 7 are shown somewhat diagrammatically the path of travel of the center of the ductor roller 14. Either position of the ductor roller may be taken as the point at which it leaves cam 39 and comes in contact with ink drum 37 or 38, but from such point of incidence the center of the ductor roller travels along the arc 40 *c*, which is concentric with the ink drum, the ductor roller thus rolling along the periphery of the ink drum. Due to the rotation or oscillation of the arm carrying the ductor roller it reaches a point where it again 45 would follow the arc *b*. This position, which is predeterminately variable, is the inter-section of the arcs *b* and *c* in Figs. 6 and 50 7, and the position *a* in Fig. 1. It will be understood that where the ductor roller 55 oscillates, as in the present embodiment, that this is preferably the approximate point of its reversal of motion.

The action at the fountain roller will be 60 clear from the foregoing without further description.

The invention in its broader aspects is not limited to the specific mechanism shown and described but departures may be made thereupon within the scope of the accompanying 65 claims without departing from the prin-

ciples of the invention and without sacrificing its chief advantages.

What we claim is:—

1. A printing press inking mechanism including in combination a fountain roller, an ink drum, and a ductor roller reciprocating between them and adapted to travel along the periphery of each and means for independently varying said travel of the ductor roller along the fountain roller and the ink 75 drum to control the supply of ink.

2. A printing press inking mechanism including in combination a fountain roller, an ink drum, and a ductor roller reciprocating between them about a center and radially movable to cause it to travel peripherally upon both the fountain roller and ink drum, and means for independently varying the radial movement of the ductor roller at the fountain roller and the ink drum to control 80 the supply of ink at both.

3. A printing press inking mechanism including in combination a fountain roller, an ink drum, and a ductor roller reciprocating between them and a device operating upon the ductor roller adjacent the fountain roller to vary the peripheral travel of the ductor roller upon the fountain roller to control the ink supply.

4. A printing press inking mechanism including in combination a fountain roller, an ink drum, a ductor roller reciprocating between them and a device operating upon the ductor roller adjacent the ink drum to vary the peripheral travel of the ductor roller 100 upon the ink drum to control the ink supply.

5. A printing press inking mechanism including in combination a fountain roller, an ink drum, a ductor roller reciprocating between them and a cam operating upon the ductor roller adjacent the fountain roller to vary the peripheral travel of the ductor roller upon the fountain roller to control the ink supply.

6. A printing press inking mechanism including in combination a fountain roller, an ink drum, a ductor roller reciprocating between them and a cam operating upon the ductor roller adjacent the ink drum to vary the peripheral travel of the ductor roller 110 upon the ink drum to control the ink supply.

7. A printing press inking mechanism including in combination a fountain roller, an ink drum, a ductor roller reciprocating between them and an arcuate cam operating upon the ductor roller adjacent the fountain roller to vary the peripheral travel of the ductor roller upon the fountain roller to control the ink supply.

8. A printing press inking mechanism including in combination a fountain roller, an ink drum, a ductor roller reciprocating between them and an arcuate cam operating upon the ductor roller adjacent the ink drum to vary the peripheral travel of the ductor 130

- roller upon the ink drum to control the ink supply.
9. A printing press inking mechanism including in combination a fountain roller, an ink drum, a ductor roller reciprocating between them and a circumferentially adjustable cam operating upon the ductor roller adjacent the fountain roller to vary the peripheral travel of the ductor roller upon the fountain roller to control the ink supply. 70
10. A printing press inking mechanism including in combination a fountain roller, an ink drum, a ductor roller reciprocating between them and a circumferentially adjustable cam operating upon the ductor roller adjacent the ink drum to vary the peripheral travel of the ductor roller upon the ink drum to control the ink supply. 75
11. A printing press inking mechanism including in combination a fountain roller, an ink drum, a ductor roller reciprocating between them and an arcuate circumferentially adjustable cam operating upon the ductor roller adjacent the ink drum to vary the peripheral travel of the ductor roller upon the ink drum to control the ink supply. 80
20. A printing press inking mechanism including in combination two ductor rollers mounted to swing about a common center, two ink drums, two fountain rollers, one ink drum and one fountain roller being substantially diametrically separated relatively to 90 said ductor roller center. 85
30. A printing press inking mechanism including in combination a fountain roller, an ink drum, a ductor roller reciprocating between them and an arcuate circumferentially adjustable cam operating upon the ductor roller adjacent the fountain roller to vary the peripheral travel of the ductor roller upon the fountain roller to control the ink supply. 95
40. A printing press inking mechanism including in combination a fountain roller, an ink drum, a ductor roller reciprocating between them about a center and resiliently radially movable to cause it to travel peripherally upon both the fountain roller and ink drum, and means for independently varying the radial movement of the ductor roller at the fountain roller and the ink drum to control the supply of ink at both. 100
50. A printing press inking mechanism including in combination two ink drums, two fountain rollers, and two diametrically opposite ductor rollers adapted to travel along the periphery of said other members. 105
55. A printing press inking mechanism including in combination two ink drums, two fountain rollers, and two diametrically opposite ductor rollers adapted to travel independently of each other along the periphery of said other members. 110
60. A printing press inking mechanism including in combination two ink drums, two fountain rollers, and two ductor rollers swinging about a common center and adapted to travel along the periphery of said other members. 115
65. A printing press inking mechanism including in combination two ink drums, 120
70. A printing press inking mechanism including in combination two ink drums, two fountain rollers, and two reciprocating ductor rollers swinging about a common center and adapted to travel along the periphery of said other members. 125
75. A printing press inking mechanism including in combination two ink drums, two fountain rollers, and two reciprocating ductor rollers swinging about a common center and adapted to travel along the periphery of said other members. 130
80. A printing press inking mechanism including in combination two ink drums, two fountain rollers, and two reciprocating ductor rollers swinging about a common center and adapted to travel along the periphery of said other members. 135
85. A printing press inking mechanism including in combination two ductor rollers mounted to swing about a common center, two ink drums, two fountain rollers, one ink drum and one fountain roller being substantially diametrically separated relatively to 90 said ductor roller center. 140
90. A printing press inking mechanism including in combination two ductor rollers mounted to swing about a common center, two ink drums, two fountain rollers, one ink drum and one fountain roller being substantially diametrically separated relatively to 95 said ductor roller center. 145
95. A printing press inking mechanism including in combination two ductor rollers mounted to swing about a common center, two ink drums, two fountain rollers, one ink drum and one fountain roller being substantially diametrically separated relatively to 100 said ductor roller center. 150
100. A printing press inking mechanism including in combination two ductor rollers mounted to swing about a common center, two ink drums, two fountain rollers, one ink drum and one fountain roller being substantially diametrically separated relatively to 105 said ductor roller center. 155
105. A printing press inking mechanism including in combination two ductor rollers mounted to swing about a common center, two ink drums, two fountain rollers, one ink drum and one fountain roller being substantially diametrically separated relatively to 110 said ductor roller center. 160
110. A printing press inking mechanism including in combination two ductor rollers mounted to swing about a common center, two ink drums, two fountain rollers, one ink drum and one fountain roller being substantially diametrically separated relatively to 115 said ductor roller center. 165
115. A printing press inking mechanism including in combination two ductor rollers mounted to swing about a common center, two ink drums, two fountain rollers, one ink drum and one fountain roller being substantially diametrically separated relatively to 120 said ductor roller center. 170
120. A printing press inking mechanism including in combination two ductor rollers mounted to swing about a common center, two ink drums, two fountain rollers, one ink drum and one fountain roller being substantially diametrically separated relatively to 125 said ductor roller center. 175
125. A printing press inking mechanism including in combination two ductor rollers mounted to swing about a common center, two ink drums, two fountain rollers, one ink drum and one fountain roller being substantially 180

diametrically separated relatively to said ductor roller center and means between each fountain roller and its ink drum for controlling the radial position of the corresponding ductor roller.

26. A printing press inking mechanism including in combination two ductor rollers mounted to yield resiliently radially and to swing about a common center, two ink drums, two fountain rollers, one ink drum and one fountain roller being substantially diametrically separated relatively to said ductor roller center and means between each fountain roller and its ink drum for controlling the radial position of the corresponding ductor roller both at the fountain roller and at the ink drum.

27. A printing press inking mechanism including in combination a fountain roller, an ink drum, a ductor roller mounted to oscillate about a center and to yield resili-

ently radially and having a path of travel somewhat longer than the radial lines connecting its center and those of the ink drum and fountain roller.

25

28. A printing press inking mechanism including in combination a fountain roller, an ink drum, a ductor roller mounted to oscillate about a center and to yield resiliently radially and a cam device between the fountain roller and ink drum independently positionable to control the cooperation of the ductor roller with each.

30

In testimony whereof, we have signed our names to this specification, in the presence of two subscribing witnesses.
